UNITED STATES PATENT OFFICE.

RICHARD JONAS, OF BERLIN, GERMANY; ASSIGNOR TO FREIBAHN GESELLSCHAFT MIT BESCHRANKTER HAFTUNG.

COMPOSITE ROAD-WAGON.

No. 918,161.

Specification of Letters Patent.

Patented April 13, 1908.

Application filed January 12, 1909. Serial No. 471,970.

To all whom it may concern:

Be it known that I, RICHARD JONAS, subject of the German Emperor, residing at Berlin, Germany, have invented new and useful 5 Improvements in Composite Road-Wagons, of which the following is a specification.

My invention relates to improvements in composite wagons of the type disclosed in United States Letters Patent No. 798,189, 10 granted on August 29th, 1904 to Arthur Koppel, Berlin, Germany, and has reference in particular to means whereby such wagons can be adapted for animal draft.

According to the present invention I provide a pole-socket and a swing-tree bracket at each end of the composite wagon, so that that wagon-body which is the front one for the time being acts, as it were, as a riding-bolster for the entire composite structure. 15 I also provide improved means for locking the longitudinal coupling-member to the wagon-bodies.

In wagons for animal draft as at present built the pole-socket and swing-tree bracket 20 are carried by a riding-bolster which is distinct from the wagon-body, and which supports the reach. In my improved wagon, on the other hand, as will be understood from the above, the front wagon-body itself 25 constitutes a kind of riding-bolster, and receives support from the reach or longitudinal coupling-member, relatively to which it has a swiveling motion.

The accompanying drawing illustrates, by 30 way of example, one form of construction of a double-wagon according to this invention.

Figure 1 is a central longitudinal section, and Fig. 2 is a plan of the improved wagon.

a, a, are the two bodies of the composite 40 wagon, each rigidly mounted on a single axle, b, so as to be incapable of rotation relatively to the said axle. Each body is located between the two high wheels, c, of its axle, b.

Underneath each wagon-body there is a 45 vertical pin, d, pivotally connecting the end of the longitudinal beam, e, to the center of the axle, whereby the front and rear axles of the composite wagon are coupled together.

Each of the two adjacent ends of the wagon-bodies is provided with a shaft, f, capable of being rocked in its bearings, g, by means of a hand-lever, h, operated from the side of the wagon. The shaft, f, is fur-

nished in the center-line of the wagon-body 55 with a fork, i. Thus, if the coupling-beam, e, occupies its central position relatively to the wagon-body, forward rocking of the shaft, f, will cause the fork, i, to engage the beam, e, and so prevent relative motion between the latter and the wagon-body. The forks, i, can be retained in their disengaged position by means of catches, k, pivoted to the side of the wagon-body. Each wagon-body, a, is provided at its other end (that is, 60 the end farthest from the companion wagon-body) with a pole-socket, l, and a swing-tree-bracket, l. A single pin, m, serves to fasten both the pole and the swing-tree in place.

In operation, the fork, i, of that one of the wagon-bodies, a, which happens to be in front, according to the direction of travel is turned up out of engagement with the beam, e, so that the front body, a, can swivel 70 horizontally relatively to the beam. The said front body, a, thus acts as a riding-bolster for the composite wagon, while the rear body, a, is locked to the beam, e, by its fork, i.

To afford proper guidance to the swiveling wagon-body and prevent its tipping, its bed is furnished with a curved plate, o, engaging in a flanged bracket, n, secured to the beam, e.

Having thus described my invention, I declare that what I claim as new, and desire to secure by Letters Patent is:—

1. A composite road-wagon, comprising, in combination, two wagon-bodies each presenting a pole-socket and a swing-tree bracket, two two-wheeled axles on each of which one body is rigidly mounted, a longitudinal member terminally pivoted to the axles and thus coupling the two wagon-bodies while admitting of their swiveling relatively to it, and a fork pivoted to each wagon-body and adapted to engage said coupling-member and prevent said swiveling motion, substantially as described.

2. A composite road-wagon, comprising, in combination, two wagon-bodies each presenting a pole-socket and a swing-tree bracket, two two-wheeled axles on each of which one body is rigidly mounted, a longitudinal member terminally pivoted to the axles and thus coupling the two wagon-bodies while admitting of their swiveling

relatively thereto, a rock-shaft mounted on each wagon - body and presenting a fork adapted to engage said coupling-member, means for turning the shaft, and a catch adapted to hold the fork in its disengaged position, substantially as described.

In testimony whereof I have signed my

name to this specification in the presence of two subscribing witnesses.

RICHARD JONAS.
